METHOD OF CONTROLLING THE FEED OF CIGARETTE TOBACCO IN CIGARETTE-MAKING MACHINES

Application filed October 20, 1925. Serial No. 63,635.

This invention relates to the method of controlling the feed of cigarette tobacco in cigarette making machines.

A feature of my invention is the provision of suitable steps for feeding cigarette tobacco to the cigarette paper, which is supplied and fed pursuant to the usual practice by means of a tube belt or the like in the formation of what is known as a cigarette rod, whereby the feed of the tobacco effects the production of cigarettes which average the predetermined weight of tobacco content required by law or in conformity to any desired weight of tobacco content.

In the practice heretofore carried out in this and foreign countries, the cigarette tobacco fed into the hopper is carded by one or more sets of suitable carding rolls or like mechanism and the carded tobacco is delivered continuously to one or more aprons for delivery to the endless strip of cigarette paper, driven by frictional contact on a so-called tube belt at a selected speed, whereafter the tube belt, cigarette paper and tobacco are passed through a so-called former or forming shoe to "roll" the cigarette paper and thereby "roll" cigarette tobacco while the resulting overlapping edge of the cigarette paper is supplied with suitable adhesive, thus forming the cigarette rod, which cigarette rod is cut by a suitable severing device into the individual cigarettes. By such procedure, the weight of the carded cigarette tobacco varies from time to time, owing to variations in the weight of the tobacco fed into the mechanism, and owing also to the differences in weight or specific gravity of the leaf, stem and other parts of the tobacco, and further owing to variations of weight or specific gravity of different grades of tobacco in the usual blended charges; further variations arise owing to the formation of air pockets within the tobacco charge and other interruptions in feeding the tobacco charge to the carding device.

It has also been proposed to deliver into the hopper and thus to the carding mechanism a charge of tobacco of predetermined quantity and to maintain the charge in the hopper at a predetermined level, to thereby

seek to attain a uniform delivery to the carding device of the tobacco charge within the hopper; however, such procedure is effected by the use of more or less cumbersome machinery for intermittently charging the tobacco within the hopper, and the results are dependent upon factors of variation of weight or specific gravity of the various constituent parts and notwithstanding produce variation in the average weight of the formed cigarettes.

Pursuant to my invention, the cigarette tobacco is fed into any form of suitable type of hopper provided with a suitable form of carding mechanism and the carded tobacco is fed to an apron in definite quantities of predetermined weight and the carded tobacco is delivered continuously from such apron to the cigarette paper in continuous amount of substantially constant predetermined weight, whereby the resulting tobacco content per unit length of the cigarette rod is of substantially constant weight and the resulting individual cigarettes possess substantially uniform weight of tobacco. The uniform weight is selected to correspond to the desired total weight of tobacco in the carton, box or other container for the cigarettes when packed, to which carton, box or other container the tax stamp is applied.

Pursuant to the most preferred form of my invention, the carded cigarette tobacco is fed to the pan of a scale or equivalent weighing device, which is set to tip at a predetermined weight, and the contents of the pan are deposited upon the apron, which is progressed at a uniform predetermined speed, the pan of the scale being again filled and its contents likewise deposited in predetermined time relation to the preceding lot dumped on the apron, such weighing and dumping being continued successively. The pan of the scale is preferably of greater length than its width and the effective rolls of the carding mechanism are of a length corresponding to the length of the pan, whereby the carded tobacco is delivered into the pan to form a mass having its length greater than its width corresponding to the length and width of the pan, and also resulting in each deposit of

tobacco on the apron of a length greater than its width. I also prefer to deposit the successive masses of carded tobacco on the apron in a uniform direction transverse to the direction of travel of the effective surface of the apron, and provide suitable mechanism for delivering continuously from the apron to the cigarette paper portions of two or more successive deposits of cigarette tobacco aggregating at all times the desired uniform quantity by weight of the tobacco.

Further features and objects of the invention will be more fully understood from the following detail description and the accompanying drawings, in which

Fig. 1 is a diagrammatic view, showing in central vertical section and partly in perspective, an assembly of any suitable hopper provided with a suitable carding mechanism, a weighing scale, and an apron and appurtenant devices for feeding the carded tobacco to an indefinite length of cigarette paper, pursuant to my invention;

Fig. 2 is a side elevation of the hopper, weighing scale and appurtenant devices illustrated in Fig. 1; the view in Fig. 2 is taken on the side of the hopper opposite to that of Fig. 1; and

Fig. 3 is a sectional elevation on line 3—3 of Fig. 1.

Referring to the drawings, and particularly to Figs. 1 and 2, the hopper may be of any suitable form and provided with a suitable set of carding devices, such as the carding roll 11 with which coacts the pin roll 12; the direction of rotation of the carding roll 11 is indicated by the arrow 13 and the direction of the pin roll 12 in the opposite direction, as shown by the arrow 14. The roll 15 serves as a feeding roll, and is rotated in the direction indicated by the arrow 16. The roll 17 is any suitable type of agitating roll.

The shaft of the carding roll 11 is indicated at 18 and is suitably mounted in bearings at 45 its opposite ends in the opposite side walls of the hopper 10, one wall 19 only being illustrated. The shaft of the pin roll 12 is indicated at 20. The shaft of the feeding roll 15 is indicated at 21 and the shaft of the agitating roll 17 at 22, both of which shafts are similarly rotatively mounted at their respective opposite ends in the hopper 10.

The hopper 10 is otherwise of any suitable arrangement, such as the provision of the belt 23 serving as the effective bottom of the hopper 10 and mounted on and driven by suitable pulleys 24, 25 in the direction of the arrow 26 to move the upper and effective length of the belt 23 in the direction of the arrow 27 and thereby feed the charge 28 of cigarette tobacco to the carding roll 11. The bottom plate 29, preferably of concave form on its face which is directed toward the carding roll 11, is disposed in close adjacency to therewith, to prevent any dropping of the

tobacco from the hopper prior to being carded by the carding mechanism.

The pin roll 12 when in its operative position relative to the carding roll 11 effects in the usual manner the delivery of the carded tobacco from the carding mechanism, indicated by the stream 30, and the paddle wheel 31 is disposed pursuant to the usual practice to act upon the stream 30 of carded tobacco.

However, pursuant to my invention, the shaft 20 of the pin roll 12 is displaceable to move the pin roll 12 into and out of operative relation with the carding roll 11 to attain the objects hereinafter more fully set forth and thus effect the formation and interruption of the stream 30 of the carded tobacco.

Upon being carded, the cigarette tobacco is weighed as by means of a beam scale, the pan of which is indicated at 32 and the adjustable weight at 33. Preferably, the pan 32 is of multiple compartment form, such as of three compartments indicated respectively 32^a, 32^b, 32^c; the pan 32 may be mounted on oppositely disposed studs 34 respectively projecting and bearing in suitable recesses in the yoke 35 of the beam 36 of the scale. The recesses of the yoke 35 are indicated at 37 and in the instance are preferably triangular of equal sides, the bottom side, see 37, being substantially horizontal and the lateral faces at each end of the stud 34 form similarly equilateral triangles, the sides of the equilateral triangle being disposed to locate the respective compartments 32^a, 32^b, 32^c in vertical i. e. receiving position respectively. At one side of the yoke 35, I provide the tripped member 38, secured to the stud 34 at that side, the tripped member 38 comprising elements corresponding in number to the number of the compartments 32^a, 32^b, 32^c, in this instance three. I provide the tripping member 39 mounted on a suitable shaft 40, and rotated continuously as hereinafter set forth, to coact with the tripped member 38 to dump the contents of the filled compartment of the pan 32 and to move the next and unfilled compartment of the pan 32 to its charging position.

As one suitable means for operating the shaft 40 of the tripping member 39, I provide the gear 41 driven in the direction of the arrow 42 by the driven gear 43 which is rotated in the direction indicated by the arrow 44. The shaft 45 of the driven gear 43 is continuously driven by any suitable means at a uniform speed conforming to the rate of travel of the apron 46 on which the cigarette tobacco is deposited as successive lots from the compartments of the pan 32. One form of such drive may comprise the beveled gear 47, meshing with the beveled gear 48 on the shaft 49 of the driving roll 50 of the apron 46. The shaft 49 of the driving roll 50 is rotated by any suitable gearing or

otherwise by the drive shaft of the cigarette making machine proper, as will be understood by those skilled in the art, to thereby drive the apron 46 at a desired rate of travel in the direction of the arrow 51, see Figs. 1 and 3, in correspondence to the rate of travel in the direction of the arrow 52 of the cigarette paper 53, effected by means of the tube belt 54 which is determined by the drive of the usual friction pulley which engages the tube belt and is driven at the proper speed from the drive of the cigarette making machine.

In Figs. 1 and 3, I have indicated a succession of deposits of the carded cigarette tobacco which have been dumped at the successive stages of filling of the respective compartments of the pan 32 and are of equal predetermined amounts by weight determined by the weight 33. The deposits are designated 55, 56, 57, 58, 59, 60, 61, and so forth. The positions of the respective deposits, and of the pan 32 and the elements of the carding mechanism show the final deposit 61 to have been discharged from the compartment 32^a, and the next compartment 32^b moved to the proper position for receiving the stream of carded tobacco 30. In the interim, the apron 46 has been moved in the direction of the arrow 51 to progress the deposit 61 of carded tobacco and the previous deposits toward the delivery end of the apron 46.

At the delivery end of the apron 46, I provide suitable means for delivering from the deposits of carded tobacco on the apron 46 into a suitable hopper 62 or equivalent for controlling and directing the delivered stream 63 of tobacco onto the indefinite length of cigarette paper 53, which passes in the usual manner through the guide 64 or equivalent.

One form of such delivery control means comprises the roll 65 provided with substantially radially extending pins 66 of relatively short and uniform length of projection for contacting with the upper surface of the apron 46, to thereby hold the portions of the deposited lots of tobacco on the belt 46 until substantially at the very delivery end of the belt 46, and further comprises the roller 67 provided with the uniformly extending pins 68 for controlling the portions of the carded tobacco delivered from the respective deposited lots at the successive stages of travel of the apron 46 to its delivery end.

It will be noted that the respective deposits of carded tobacco dumped on the apron 46 are uniformly aligned at an angle to the direction 51 of longitudinal travel of the apron 46, whereby there is presented to the delivery control means 65, 67 at substantially all times two or other uniform number of such deposited lots. In the position of these parts as shown in Fig. 3, and correspondingly in Fig. 1, (bearing in mind that the de-

livery control means 65, 67 is omitted in Fig. 3 for the sake of clarity), it will be observed that portions of the deposited lots 55, 56 are jointly delivered into the hopper 62, and as such action continues, a portion of the deposited lot 57 will attain its stage of delivery simultaneously with portions of the deposited lots 56, 55 until ultimately the whole of the remainder of the deposited lot 55 will have been discharged from the apron 46, a similar action takes place for the remainder of the deposited lots 56, 57, including after a stage at which a portion of the next deposited lot 58 is simultaneously discharged therewith from the apron 46.

It will be further observed that the roll 65 serves in the nature of a carding roll, in which operation the tobacco progressed by the apron into contact with the pins 66 of the roll 65 from the respective spaced deposited lots, such as the lots 55, 56, are distributed substantially uniform about the periphery and longitudinally of the direction of length of the roll 65, and that the roll 67 serves in the nature of a pin roll, similar to the aforesaid pin roll 12, to effect the removal of the tobacco from the pins 66 of the roll 65 substantially uniformly along the direction of length of the periphery of the roll 65 and thereby substantially uniformly distribute the tobacco in the stream 63 discharged into the hopper 62, or equivalent, and thereby substantially uniformly distribute the tobacco deposited upon the cigarette paper 53 and thus form cigarettes having substantially uniform content of tobacco per unit length. The rolls 65, 67 are driven from the drive of the cigarette making machine or the drive of the apron 46 to deliver carded cigarette tobacco to its cigarette paper at a substantially constant rate equal to average amount by weight of tobacco conveyed in the form of deposits spaced from one another on the apron 46 per unit of the length of the apron 46. It will be noted that the disposition of the deposits on the apron 46 at an angle to the direction of travel of the apron 46 facilitates the equalization of distribution of the contents of the spaced deposits on the roll 65 and averages up any variations of specific gravity of the tobacco owing to the presence of relatively heavy leaf, or of stems or the like.

For the purpose of controlling the depositions of lots of substantially uniform weight of carded tobacco on the apron 46 or equivalent, I provide suitable means for effecting the flow 30 of carded tobacco into a compartment of the pan 32 of the scale 31 and to interrupt such stream 30 at the instant of filling such compartment with the desired weight of tobacco, the movement of the next compartment to its filling position. As one manner of carrying out such step, I provide electrically controlled parts including the contact 70, insulatingly carried by the beam 36 of the

scale, which contact 70 is connected to the conductor 71 to one terminal of the battery 72 or other suitable source of electrical energy, the other terminal of the battery 72 being connected by the conductor 73 to the terminal 74 of the coil of the solenoid 75, the opposite terminal 76 of which is connected by the conductor 77 to the contact 78 co-operating with the aforesaid contact 70.

10 The contact 78 is mounted on a suitable support, either of insulating material or electrically insulated by means of suitable insulation; I have indicated the bracket 79 which is mounted on and extends above the base 80 of the scale 31 as one form of support for the contact 78.

15 The stop 79^b for the beam 36 of the scale is preferably adjustable to thereby regulate the spacing between the contacts 70, 78, when a compartment of the pan 32 is at the stage 20 of being filled. Upon such compartment being filled to the amount regulated by the weight 33, the beam 36 of the scale is tilted on the contact 70 is moved into contact with the fixed contact 78, thereby closing the circuit through the source 72 and energizing the coil of the solenoid 75, and thereby throwing the pin wheel 12 from its position of operativeness relative to the carding roll 11 to 25 a position of non-operation.

20 The gears 41, 43 may be suitably rotatably mounted at the ends of their respective shafts in oppositely disposed, vertically extending standards 79 (one only being shown) secured 30 to a base 79^a.

25 As one suitable form of mounting for the pin wheel 12, its shaft 20 of the pin wheel 12 is secured to one end of the angular arm 81. The arm 81 is freely mounted intermediate 35 its length on an end of the shaft 82 of the pulley 82^a, to provide pivotal movement of the arm 81, and the opposite end of the arm 81 is provided with an opening for receiving the free end of the guide rod 83, the fixed end 40 of which guide rod 83 is pivotally secured to the side wall 19 of the hopper 10. The expansive spring 85 is coiled about its guide rod 83, to bias the arm 81 to move the shaft 20 of the pin wheel 12 toward the carding roll 50 11. The stop 86 serves to limit the throw of the arm 81 under action of its spring 85.

55 The idler pulley 82^a is driven by the belt 87, driven by the pulley 88 fixed on the shaft 18 of the carding roll 11, and the pulley 89 fixed on the shaft 31^a of the paddle wheel 81 is driven by the belt 90 from the pulley 82^a, and similarly the belt 91 driven from the pulley 88 drives the pulley 92 fixed on the shaft 20 of the pin wheel 12. The driving of the 60 belts 90, 91 is preferably by means of sets of doubled pulleys respectively secured to one another, to provide a single belt for each pulley of the respective sets. The movement of the arm 81 and therewith the movement of the 65 pin wheel 12 into non-operative relation with

its carding roll 11 is effected by the solenoid 75 when excited by electrical current as above described by any suitable means, such as the core 93 of the solenoid 75 being pivotally connected to the arm 81 as at the location 94.

70 The return of the pin wheel 12 to its operative position, and a similar movement of the paddle wheel 31, as above indicated, ensues upon the de-energization of the coil of the solenoid 75 upon the breaking of the circuit 75 by the contact 70 on the scale beam 36 being moved from engagement with the contact 78 when the tobacco contents of a filled compartment of the scale pan 32 has been deposited upon the apron 46 and actuated by the spring 80 85, as above stated.

85 The carrying out of my invention will be understood from the foregoing. It will be perceived, however, that upon excitation of the solenoid 75, arising upon the closure of the electrical circuit by the tipping of the scale beam 36 when a compartment of the scale beam pan 32 has been filled. A short interval of time elapses between the instant when the pin roll 12 is withdrawn from the carding roll 90 11 and the instant when the remainder of the interrupted stream 30 of the carded tobacco drops into the compartment, including its passage past the paddle wheel 31, thereby adding to the content of the compartment of the scale 95 pan 32 beyond the weight determined by the setting of scale weight 33, and such additional weight is compensated by setting the scale weight 33 to tip the scale beam 36 at a position correspondingly less than the predetermined content by weight for the respective 100 deposits of carded tobacco on the apron 46. It will be observed that the interval of time required to fill a compartment is less than the interval of time between the instants of tripping of the tripped member 38.

105 It will be understood that the apparatus above described may be varied in arrangement as will appear clearly to those skilled in the art upon understanding my invention. 110 Preferably, the apparatus affords the continuous operation of the carding mechanism notwithstanding the interruption of the stream of carded tobacco and thereby maintain the carding mechanism in primed condition to effect the restoration of the stream of carded tobacco to the weighing device substantially instantly upon the pin wheel or equivalent element being resorted to its operative position. The apparatus also preferably provides for relatively increased number of deposits per length of the apron or equivalent and correspondingly relatively decreased spacing between the deposits on the apron.

115 Whereas, I have described my invention by reference to specific forms thereof, it will be understood that many changes and modifications may be made without departing from the spirit of the invention.

I claim:—

1. The method of feeding tobacco to a length of the cigarette paper for producing cigarettes of uniform predetermined content of tobacco by weight per unit length, which comprises weighing the carded cigarette tobacco, distributing the weighed carded tobacco substantially uniformly on a suitable feeding apron as masses separated from one another, each mass extending at an angle to the direction of travel of such feeding apron, maintaining the travel of such feeding apron in the direction of its length substantially uniformly and inclusive of the periods of depositing of such masses upon such feeding apron, and substantially continuously feeding the carded tobacco from such feeding apron to the length of the cigarette paper.
2. The method of feeding tobacco to a length of the cigarette paper for producing cigarettes of uniform predetermined content of tobacco by weight per unit length, which comprises weighing the carded cigarette tobacco in successive substantially equal amounts respectively distributing the weighed carded tobacco substantially uniformly on a suitable feeding apron as masses separated from one another, each mass extending at an angle to the direction of travel of such feeding apron, maintaining the travel of such feeding apron in the direction of its length substantially uniformly and inclusive of the periods of depositing of such masses upon such feeding apron, and substantially continuously feeding the carded tobacco from such feeding apron to the length of the cigarette paper.
3. The method of feeding tobacco to a length of the cigarette paper for producing cigarettes of uniform predetermined content of tobacco by weight per unit length, which comprises weighing the carded cigarette tobacco in successive substantially equal amounts respectively, distributing the respective weighed amounts on a suitable feeding apron as masses separated from one another, each mass extending at an angle to the direction of travel of such feeding apron, maintaining the travel of such feeding apron in the direction of its length substantially uniform and inclusive of the periods of depositing of such masses upon such feeding apron, and distributing to the cigarette paper from the conveyor the tobacco in substantially uniform weight per unit length of cigarette paper.
4. The method of feeding tobacco to a length of the cigarette paper for producing cigarettes of uniform predetermined content of tobacco by weight per unit length, which comprises weighing the carded cigarette tobacco in successive substantially equal amounts respectively, distributing the respective weighed amounts on a suitable conveyor as segregated masses, each of said spaced deposits being deposited on said conveyor as a segregated mass, each mass having a length substantially greater than its breadth, the direction of length of each mass extending at an angle to the direction of travel of said conveyor and distributing to the cigarette paper from the conveyor the carded tobacco in substantially uniform weight per unit length of cigarette paper by withdrawing carded tobacco from said conveyor in a direction substantially the direction of travel of said conveyor.
5. The method of feeding tobacco to a length of the cigarette paper for producing cigarettes of uniform predetermined content of tobacco by weight per unit length, which comprises weighing the carded cigarette tobacco in successive substantially equal amounts respectively, distributing the respective weighed amounts on a suitable conveyor in spaced deposits thereon, each of said spaced deposits being deposited on said conveyor as a segregated mass, each mass having a length substantially greater than its breadth, the direction of length of each mass extending at an angle to the direction of travel of said conveyor, imparting a substantially uniform travel to said conveyor, withdrawing the carded tobacco from said conveyor to the length of cigarette paper in the direction of travel of said conveyor, and distributing to the cigarette paper from the conveyor the tobacco in substantially uniform weight per unit length of cigarette paper.
6. The method of feeding tobacco to a length of the cigarette paper for producing cigarettes of uniform predetermined content of tobacco by weight per unit length, which comprises weighing the carded cigarette tobacco in successive, substantially uniform amounts respectively, distributing the weighed carded tobacco substantially uniformly on a suitable conveyor as masses segregated from one another, each mass having a length substantially greater than its width, the direction of length of each mass extending at an angle to the direction of travel of the conveyor and feeding the carded tobacco from the conveyor to a length of cigarette paper by withdrawing tobacco simultaneously from a plurality of such segregated masses.
7. The method of feeding tobacco to a length of the cigarette paper for producing cigarettes of uniform predetermined content of tobacco by weight per unit length, which comprises weighing the carded cigarette tobacco in successive, substantially uniform amounts respectively, distributing the respective weighed amounts on a suitable conveyor as segregated masses, each mass having a length substantially greater than its width, the direction of length of each mass extending at an angle to the direction of travel of the conveyor.

- travel of the conveyor, and distributing to the cigarette paper from the conveyor the tobacco in substantially uniform weight per unit length of cigarette paper by feeding tobacco from the conveyor to the cigarette paper by withdrawing tobacco simultaneously from a plurality of such segregated masses in a direction substantially that of the travel of said conveyor.
8. The method of feeding tobacco to a length of the cigarette paper for producing cigarettes of uniform predetermined content of tobacco by weight per unit length, which comprises weighing the carded cigarette tobacco in successive, substantially uniform amounts respectively, distributing the respective weighed amounts on a suitable conveyor in spaced deposits thereon, each mass having a length substantially greater than its width, the direction of length of each mass being at an angle to the direction of travel of the conveyor, and distributing to the cigarette paper from the conveyor the tobacco in substantially uniform weight per unit length of cigarette paper by feeding the tobacco from the conveyor to the cigarette paper by withdrawing simultaneously from a plurality of such segregated masses in a direction substantially that of the travel of the conveyor.
9. The combination of a mechanism for carding tobacco including a carding roll and a pin wheel, the pin wheel controlling the amount of the carded tobacco delivered from the carding roll, a weighing device, means for moving the pin wheel into and out of operative relation with the carding roll to thereby create and interrupt the stream of carded tobacco delivered from the carding mechanism and means controlled by the weighing device for operating said pin wheel moving means.
10. The combination of a mechanism for carding tobacco including a carding roll and a pin wheel, the pin wheel controlling the amount of the carded tobacco delivered from the carding roll, a weighing device, means for moving the pin wheel into and out of operative relation with the carding roll to thereby create and interrupt the stream of carded tobacco delivered from the carding mechanism, means controlled by the weighing device for operating said pin wheel moving means, a conveyor for receiving the amounts of tobacco weighed by said weighing device and means for delivering the amounts received by said conveyor in weight equalized distribution to the cigarette paper.
11. The combination of a mechanism for carding tobacco including a carding roll and a pin wheel, the pin wheel controlling the amount of the carded tobacco delivered from the carding roll, a weighing device, means for moving the pin wheel into and out of operative relation with the carding roll to thereby create and interrupt the stream of carded
- tobacco delivered from the carding mechanism, means controlled by the weighing device for operating said pin wheel moving means, a conveyor for receiving the amounts of tobacco weighed by said weighing device and means for delivering the amounts received by said conveyor in weight equalized distribution to the cigarette paper, said delivery means comprising a roll having pins distributed substantially uniformly on its periphery and having a length substantially from one edge of the conveyor to the opposite edge and a second roll having delivering pins on its periphery and having a length substantially that of said first-named delivery roll.
12. The method of carding tobacco to a length of the cigarette paper for producing cigarettes of uniform predetermined content of tobacco by weight per unit length, which comprises weighing the carded cigarette tobacco in successive, substantially uniform amounts respectively, distributing the respective weighed amounts on a suitable conveyor in spaced deposits thereon, each deposit having a length substantially greater than its width, the direction of length of each deposit being at an angle to the direction of travel of the conveyor, distributing the tobacco from the conveyor to the cigarette paper in substantially uniform weight per unit length of cigarette paper by imparting a substantially uniform travel to said conveyor and by feeding the tobacco from the conveyor to the cigarette paper by withdrawing simultaneously from a plurality of such segregated deposits.
- In testimony whereof I have signed this specification this 18th day of August, 1925.
- WILLIAM F. GRUPE.
